TIRE

Samuel Wilkens, 966 Wateredge Place,
Hewlett Harbor, N.Y. 11557

Filed May 4, 1970, Ser. No. 22,791

Term of patent 14 years

Int. Cl. D12—14

U.S. Cl. D90—20

FIG. 2

FIG. 1

FIG. 3

FIG. 4

FIG. 1 is a perspective view of a tire showing my new design;

FIG. 2 is a cross-sectional view along the lines 2—2 of FIG. 1;

FIG. 3 is a cross-sectional view similar to FIG. 2, but showing another embodiment of the tire of my invention; and

FIG. 4 is a greatly enlarged fragmentary view of the tread design of both forms of the tire.

I claim:

The ornamental design for a tire, substantially as shown and described.
